UNITED STATES PATENT OFFICE.

DAVID PATTERSON FINNEY, OF CLAIRTON, PENNSYLVANIA.

COKE-HANDLING MECHANISM.

Application filed December 4, 1925. Serial No. 73,166.

This invention relates to material storage platforms and handling mechanism, and more particularly to inclined storage platforms such as coke wharfs which include an endless conveyer for conveying the material away from said platform, and has for its object the provision of a novel form of control and feeding mechanism for controlling the discharge of material from the platform and guiding such material onto the endless conveyer.

Another object is to provide a novel form of control and feeding mechanism especially adapted for use with coke wharfs whereby the handling of the coke is facilitated and less breakage of the coke and wear of the mechanism is had than with mechanism heretofore in use.

A further object is to provide control and feeding mechanism having the novel design, construction and combination of parts hereinafter described and illustrated in the accompanying drawings.

In the drawings:

Figure 1 is a sectional elevation through the lower portion of a coke wharf having my invention applied thereto.

Figure 2 is a sectional elevation on the line II—II of Figure 1.

Referring more particularly to the drawings, the numeral 2 designates the storage platform or wharf which is inclined so as to permit the coke or other material to slide downwardly by gravity and onto an endless conveyer 3 located below the lower edge thereof.

A suitable supporting structure 4 is provided for supporting the endless conveyer 3, material control gates A and material feeding or distributing mechanism B.

The gates A are each composed of a curved or convex imperforate cut-off plate 5 provided with teeth 6 along its longitudinal edges and secured to a supporting frame 7. The gate frames 7 are provided with lugs or ears 8 which are pivotally or hingedly secured at 9 to lugs 10 on a beam 11 mounted on the supporting frame or structure 4. Each of the gate frames 7 are provided with rearwardly extending counterweight arms 12 to facilitate the operation of the gates, and hand-holds 14 are provided at the upper ends of the gate frames for the operator to grasp when operating the gates.

When coke is dumped onto a coke wharf it is still warm and occasionally there are hot

spots which are incandescent. This condition creates a natural draft along the wharf, which draft at times will cause combustion of the incandescent coke. By the use of the imperforate gate or cut-off plate this natural draft is materially reduced and, therefore, there is less likelihood of the combustion of the hot spots in the coke.

The feeding or distributing mechanism B, comprises an open bottom trough-like member or chute composed of side plates 16, and transverse feeding and guide plates 17 are supported on the structure 4 between the wharf 2 and conveyer 3 and is adapted to deliver the coke onto the conveyer.

The transverse feeding and guide plates 17 are spaced longitudinally of the side plates 16 and are inclined downwardly in the direction of travel of the conveyer 3 so that the coke or other material flowing onto said plates will have its direction of travel changed and will be compelled to slide down over said plates so as to be fed onto the conveyer in a uniform manner with very little drop and consequently with minimum breakage.

A bridge plate 19 extends between the platform or wharf 2 and the chute so as to permit the coke or other material to flow by gravity from the wharf 2 into the chute when the gates A are opened.

A pair of side retaining plates 20 are secured to the structure 4 and extend along each side of the conveyer 3 to prevent spillage from the conveyer.

In operation the gates A are opened to permit the coke or other material to flow by gravity into the chute where the plates 17 will intercept said material so as to retard its flow and change its direction. The plates cause a uniform feed of the material with a very short vertical drop, thereby materially reducing breakage of the material and wear of the conveyer.

While I have shown and described one specific embodiment of my invention it will be understood that I do not wish to be limited thereto, since various modifications may be readily constructed without departing from the scope of my invention as defined in the appended claims.

I claim:

1. The combination with an endless conveyer for lump material such as coke, of a guide mechanism for guiding the material onto said conveyer, said guide mecha-

- nism comprising spaced side plates mounted above and extending in a direction longitudinally of said conveyer, and a plurality of feeder plates mounted between said side plates and spaced longitudinally thereof, said feeder plates being inclined downwardly and in the direction of travel of said conveyer, so as to feed the material onto said conveyer uniformly and with a minimum drop.
2. The combination with an endless conveyer for lump material such as coke, of a guide mechanism for guiding the material onto said conveyer, said guide mechanism comprising spaced side plates mounted above and extending in a direction longitudinally of said conveyer to form an open bottom trough above said conveyer, a plurality of feeder plates mounted between and secured to said side plates and spaced longitudinally thereof, said feeder plates being inclined downwardly as in the direction of travel of
- 10 15 20

said conveyer, so as to feed the material onto said conveyer uniformly and with a minimum of drop, and conveyer side plates arranged below said first mentioned side plates to prevent spillage from said conveyer.

3. The combination with an endless conveyer for lump material such as coke, of a guide mechanism for guiding the material onto said conveyer, said guide mechanism comprising spaced side plates mounted above and extending in a direction longitudinally of said conveyer, and a plurality of feeder plates mounted between and secured to said side plates and spaced longitudinally thereof, said feeder plates being inclined downwardly and in the direction of travel of said conveyer, so as to feed the material onto said conveyer uniformly and with a minimum of drop.

In testimony whereof, I have hereunto set my hand.

DAVID PATTERSON FINNEY.
